UNITED STATES PATENT OFFICE.

ADOLF MEYER, OF ZURICH, SWITZERLAND, ASSIGNOR TO AKTIENGESELLSCHAFT
BROWN BOVERI & CIE., OF BADEN, SWITZERLAND.

MEANS FOR FASTENING THE BLADES IN GAS TURBINES AND STEAM TURBINES.

Application filed December 20, 1922. Serial No. 608,109.

To all whom it may concern:

Be it known that I, ADOLF MEYER, a citizen of the Swiss Republic, residing at Zurich, Switzerland, have invented certain new and useful Improvements in Means for Fastening the Blades in Gas Turbines and Steam Turbines, of which the following is a specification.

A known method of fastening the blades in gas turbines and steam turbines has been to suspend them from the spacing members, the spacing members themselves being fixed in the wheel discs or drums. In such cases the fixing of the spacing members has been effected hitherto mostly by means of round, rectangular or saw-tooth shaped projections engaging in corresponding grooves in the drum or disc.

Since, in view of the high strains, the shank of the blade must not be weakened, the designer has been compelled to allow these projections or teeth of the blades to project beyond the edge of the blade, thus entailing at the same time an extra thickening of the head of the disc.

This accumulation of material at the outer periphery is an undue load on the wheel disc, and has given rise to high stresses in the disc, or it has compelled the thickening of the edge of the disc, with the result of increasing the consumption of expensive material and the cost of manufacture.

It is also known to make the blades of the last rows of turbines, which are the blades most strained, in one piece with the spacing member, and to cause the blade-foot, strengthened in this manner, to clasp the edge of the disc for the purpose of being fastened thereto and thus producing a lighter rim for the disc. This necessitates however, the milling of the blades out of the solid cross-section of the foot, and consequently a very considerable increase in the cost of manufacture.

The present invention has for its object to allow of the use of light rims for the wheel discs, and to diminish the strains on the discs, even when employing the indirect way of fastening the blades by means of the spacing members.

This is effected by causing the spacing members which carry the blades, to clasp the edge of a wheel disc in the manner illustrated

by way of example in the figures of the accompanying drawings in which:—

Figure 1 is a radial cross-section of a turbine wheel disc comprising one embodiment of this invention.

Figures 2 and 3 are similar views of two further embodiments.

Figure 4 is a section, and

Figure 5 is a section partly in front elevation, and

Figure 6 is a plan of a number of blades fastened to the wheel disc.

In this construction the spacing members and the blades may be equal in width, that is to say, the rim of the wheel disc may be made narrower than the blades as shown in Figure 1, or the spacing members may be made wider than the blades, in which case the width of the rim of the wheel disc is made equal to or approximately equal to the width of the blades as shown in Figure 2.

In order to protect the clasping parts *a* of each spacing member from bending strains, the spacing members may be provided with projections *b* which engage in corresponding grooves turned in the disc as shown in Figures 2 and 3; this expedient being already known per se in the case of blades made in one piece with the spacing member.

The blades of the improved blade-fastening are provided, preferably by upsetting, with a T-shaped blade-foot which is clamped and held firmly between two adjacent spacing members. These blades can then bear directly upon the rim of the discs as shown in Figures 4 and 5.

It may also be mentioned that the spacing members *a* clasping the edge of the wheel disc can be arranged with their outer surfaces so close together as to form a smooth surface obviating all windage.

The invention produces a blade-fastening of great simplicity and cheapness even for blades subjected to high strains, because the blades as well as the spacing members can be made from drawn bars. The spacing members merely require to be cut to the length and formed with a recess corresponding to the cross-section of the rim of the disc, whereas the blades are provided by upsetting, with their feet or projections with which they are fitted between the spacing members.

By suitably cutting off the spacing members on the steam side (edge *d*) the cross-sectional passage area can be adapted very simply to the steam conditions.

5. What I claim is:—

1. In a means for fastening turbine blades to a wheel disc in a steam or gas turbine of the type wherein the turbine blades are carried by the blade-spacing members, the

10. combination with the wheel disc having an under-cut rim and a turbine blade, of a blade-spacing member carrying said blade clasping the under-cut rim of the wheel disc.

2. In a means for fastening turbine blades to a wheel disc in a steam or gas turbine, of the type wherein the turbine blades are carried by the blade-spacing members, the combination with the wheel disc having an under-cut rim, and a turbine blade, of a 20 blade-spacing member carrying said blade, clasping the under-cut rim of the wheel disc, and a T-shaped foot on said turbine blade, bearing upon the under-cut rim of the wheel disc.

25. 3. In a means for fastening turbine blades

to a wheel disc in a steam or gas turbine of the type wherein the turbine blades are carried by the blade-spacing members, the combination with the wheel disc, having an under-cut rim and a turbine blade, of a blade-spacing member carrying said blade, wider than said blade, clasping the under-cut rim of the wheel disc. 30

4. In a means for fastening turbine blades to a wheel disc in a steam or gas turbine of the type wherein the turbine blades are carried by the blade-spacing members, the combination with the wheel disc having an under-cut rim and a turbine blade, of a blade-spacing member carrying said blade, clasping the under-cut rim of the wheel disc, an annular groove in the side of the wheel disc, and a projection located on said blade-spacing member, engaging in said annular groove, whereby the clasping parts of said 40 blade-spacing member are relieved from bending strains. 45

In testimony whereof I have signed my name to this specification.

ADOLF MEYER.
